UNITED STATES PATENT OFFICE

2,615,519

PLUG HANDLING HEAD FOR WELL CASINGS

Charles J. Carr, Long Beach, Calif.

Application June 30, 1947, Serial No. 758,184

3 Claims. (Cl. 166—14)

1

This invention has to do with a plug handling head applicable to a well casing and it is a general object of the invention to provide a simple, practical, improved structure of this general character.

Plugs are used in connection with or incidental to cementing operations carried on in oil wells, it being common to employ two plugs one a leading plug to precede a body of cement into a well and the other a trailing plug which follows the body of cement. Devices known as cementing heads have been proposed and used to facilitate the introduction of the plugs into the well.

My present invention is primarily concerned with a head applicable to a well casing or the like for handling plugs and through which mud, cement, or other material may be pumped or circulated in the process of carrying out a cementing operation.

It is an object of my invention to provide a cementing head which is compact vertically and which may be employed to handle a plurality of plugs. By providing a vertically compact structure I have a device which is easily manipulated and which can be quickly moved into position over the well where it occupies a minimum of space.

A general object of my present invention is to provide a cementing head which will handle a plurality of plugs and which includes means for handling the fluid introduced into the well, which head is simple, compact, and easily handled. The head construction that I have provided is in the form of a unit requiring but two connections to be made in order to apply it to a well for operation, one the connection between the head and the well and the other between the head and a supply hose or the like delivering fluid to the head.

Another general object of the present invention is to provide a head of the general character referred to involving a fluid handling system whereby fluid can be easily, conveniently and effectively directed to different parts of the head as the head is operated, to the end that fluid such as mud is initially introduced under a lower plug in the head while cement may later be introduced into the head above the lower plug and below an upper plug located in the head, and finally mud may be introduced into the head above the upper plug.

Fig. 1 is a view showing the structure of the present invention in operating position on the upper end of a well casing, certain parts of the construction being broken away to show in section and the structure being shown carrying two plugs and in condition ready for operation. Fig. 2 is a plan section taken as indicated by line 2—2 on Fig. 1. Fig. 3 is a side elevation of parts shown in Fig. 1, certain parts being shown in section and showing the lower plug in the process of passing the control latch which normally supports it in

2

the head. Fig. 4 is an enlarged elevation of a part of the head showing a latch mechanism included in the construction. Fig. 5 is a detailed sectional view of the part shown in Fig. 4 being a view taken as indicated by line 5—5 on Fig. 4. Fig. 6 is a transverse sectional view of the parts shown in Fig. 4 being a view taken as indicated by line 6—6 on Fig. 4. Fig. 7 is a side elevation of the construction shown in Fig. 4 certain of the parts being shown in section on the line indicated as 7—7 on Fig. 4, and Fig. 8 is a view similar to Fig. 5 showing the latch released and the plug previously supported by the latch in process of passing the latch.

The construction that I have provided involves, generally, a tubular body 10, releasable coupling means 11 coupling the body to the upper end of the well casing or the like, a cap 12 closing the upper end of the body, a stop plug 13 carried by the cap in the upper end of the body to form a stop for the uppermost plug A carried in the body, supporting means 14 provided to facilitate simple quick handling of the head, releasable stop means 15 supported by the body 10 and controlling movement of plugs within the head, pressure equalizing means 16 communicating with various portions of the head, fluid supply means 17 coupled to the body 10 and serving to supply fluid to various parts thereof as required, and various other features of construction as will be hereinafter described.

The body 10 in accordance with the preferred form of my invention is a simple, vertically disposed tubular element the interior of which is of substantially the same diameter as the well casing C to which the head is to be applied, or at least it is of such size as to accommodate plugs operable in the casing. The body 10, as shown in the drawings, is a simple straight tubular part with its lower end open or in communication with the upper end of the casing C and with its upper end closed by the cap 12.

The coupling means 11 is a releasable coupling and serves to releasably connect the lower end of the body 10 to the upper end of the casing C and since my present invention is in no way concerned with the details of such coupling or connection I have merely indicated a conventional coupling of a type that is quick acting and which will serve to effectively and securely couple the body 10 to the casing C.

The cap 12 serves primarily as a closure for the upper end of the body 10 and in practice it may be secured to the body in any suitable manner. In the case illustrated the cap is shown provided with a depending flange 18 screw threaded to the upper end of the body 10.

The plug stop 13 that I provide is located in the upper end portion of the body 10 and serves as a positive stop to limit upward movement of

the uppermost plug A in the body, the stop serving to position the plug A in the body so that there is a chamber or space X left in the body above the plug or between the plug and the cap, as clearly shown in Fig. 1 of the drawings. In accordance with the preferred form of my invention the stop 13 is carried by the cap 12 and when this construction is employed the stop may be in the form of a depending projection 20 extending downwardly from the lower end of a shank 21 centrally threaded in the cap. A lock nut 22 is shown applied to the shank to set it in the desired position in the cap. In practice the projection 20 depends a suitable distance into the body 10 from the cap and is such as to engage a suitable part of the plug A, as for instance, the core 23 of the plug as shown in Fig. 1. It is to be observed that the projection 20 extends far enough down into the body 10 to stop the plug A so that its upper end is spaced somewhat below the lowermost part of the cap, that is below the flange 18 of the cap.

The supporting means 14 provided to facilitate handling of the head is preferably a swivel connection applied to or carried by the cap 12 and is such as to make connection with an operating line L, or the like. In the case illustrated the means 14 is shown as including a yoke-shaped bracket 24 rotatably supported on an upward extension 25 of shank 21 and carrying a horizontally disposed pivot pin 26 which holds a rope socket 27 or the like which, in turn, receives and holds the line L. Through this construction the head is readily rotatable relative to the line L and can freely swing about the pivot pin 26, making the head easy to handle in the derrick in the course of being applied to or removed from the casing C.

The releasable stop means 15 includes one or more units, preferably like units, and in a typical case where the head is to handle two plugs, an upper plug A and a lower plug B, the structure includes two stop units. Each stop unit is preferably in the nature of a latch mechanism and, in accordance with the construction that I have provided each latch unit is such that it may serve either to stop downward movement of a plug, upward movement of a plug, or it may even simultaneously stop downward movement of one plug while it stops upward movement of the other plug, stopping such plugs in spaced relation within the body.

In the particular case illustrated the head involves two stop units or two units of the means 15 which units are alike and the uppermost of which is located to serve as a stop to prevent downward movement of the upper plug A at the same time that it prevents upper movement of the lower plug B, while the lowermost unit is located to serve solely as a stop for downward movement of the lowermost plug. In practice I may employ a plurality of units serving to stop plugs in both directions. In cases where the plugs require greater support than is afforded by one unit, for instance, when the plugs used and the head employed are of large diameter, a plurality of units 15 may be used at a single point lengthwise of the head, and such units may be suitably spaced around the body 10 of the head.

I will describe but one of the units of means 15, for example the uppermost unit, as shown in the drawings, it being understood that such description is applicable to both units or to as many units as may be included in the head.

The stop means 15 in its preferred form involves, primarily, a shiftable latch 30 and suitable supporting and controlling means for the latch. In the case illustrated the latch 30 is a pivoted latch, in which case it is carried on a rotatable shaft 31 and the shaft in turn is rotatably supported by a housing 32. A stop 33 on the latch positively stops the latch in full operating position where it prevents movement of a plug in either direction past it in the body 10. A means 34 preferably, a spring means, serves to normally yieldingly hold the latch in full operating position and a manually operable control means 35 controls operation of the latch, preferably through the supporting shaft 31. In the preferred form of the invention I provide indicating means 36 whereby the operator can readily determine the position of the latch.

The latch 30 in the preferred form of construction is in the nature of a latch plate 40 carried by the shaft 31 which is located outside of the body 10 and having a plug stopping portion normally projecting into the body 10 through a latch opening 43 provided in the side of the body. In the particular form of latch illustrated the portion which projects into the body to stop the plug or plugs as the case may be is somewhat triangular in form and has an upper stop face 44 to be engaged by the lower end of a plug above the latch and has a lower stop face 45 to be engaged by a plug below the latch. The top face 44 in the case illustrated is a straight or flat face shaped and proportioned to suitably engage the lower end portion of the upper plug A while the lower face 45 is a curved face concentric with the axis of shaft 31.

The stop 33 provided on the latch 30 is in the nature of a projection on the latch plate 40 at which may be termed the inner end of stop face 45 the projection being proportioned to engage a suitable fixed part to positively limit inward swinging movement of the latch plate in the manner indicated in Fig. 5 of the drawings.

The housing 32 may be a cup-shaped structure applied to the exterior of the body 10 at the opening 43 to provide a latch chamber 46 which is closed except for access to the interior of the body 10 through the opening 43. In the case illustrated a suitable mounting pad 50 is provided on the exterior of the body 10 surrounding the opening 43 to carry the housing 32. The housing 32 is shown as including spaced vertical sides 51 and 52, an outer end 53 extending between the sides, a top 54 and a bottom 55, these various parts of the housing being preferably integrally joined, in which case the housing may be a simple cast unit.

The shaft 31 carrying the latch plate extends through the latch chamber 46 between the sides 51 and 52 of the housing and it is rotatably supported in suitable bearing openings 56 in the sides of the housing.

The means 34 provided to normally yieldingly urge the latch to normal position may include a simple compression spring 68 located in the latch chamber 46 between the top 54 of the housing and a shoulder 69 on the latch plate, these parts being located and related so that the spring operates between an extended or fully operating position, as shown in Fig. 5 and a compressed position as shown in Fig. 8.

The control means 35 for the latch 30 preferably controls the latch through the shaft 31 and in the particular form illustrated in the drawings the means 35 involves a latch pin that

is manually operable and which is carried by the housing to cooperate with the shaft 31. The shaft 31 is provided at one end with an enlargement or head 70 which operates in a chamber 71 provided in the wall 52 of the housing, the outer end of the chamber being closed by a removable plug 72. The head 70 has a flattened side 73 normally engaged by the pin.

The latch pin is shown carried by a boss 75 on the housing and in the form illustrated it includes an inner control end portion 76 which engages and cooperates with the flat side 73 of head 70, and it includes a shank 77 located within the boss and carrying a stem 78 which projects at the exterior of the boss. The pin just described is slidably carried in a bore 79 provided in the boss 75 and a suitable handle or head 80 is provided on the outer end of the portion 78 to facilitate convenient manual operation of the stem.

When the latch pin is down or in operating position, as shown in Fig. 7, the control end 76 is in engagement with the flat side 73 of the head 70 on shaft 31, thus positively preventing rotation of the shaft from a position where the latch plate 40 is in plug stopping position as shown in Fig. 5. When the pin is operated, that is, when it is moved upwardly from the position just described, the control end 76 of the pin is disengaged from the head on the shaft leaving the shaft free to rotate under the influence of pressures or forces that may be exerted on the latch plate through a plug engaging the latch plate. For example, when the latch pin is released or disengaged from the head of the shaft the latch plate is free to rotate except for the resistance of spring 68 so any appreciable downward pressure on the plug engaging the stop face 44 of the latch plate will cause the latch plate to be depressed or released to the position shown in Fig. 8, whereupon the plug is free to slide past the latch in order to enter the well casing to which the head is connected.

In the preferred form of my invention I provide detent means for releasably holding the latch pin either in the operating or down position, or in the released position. In the case illustrated a spring pressed detent 81 is carried by the boss 75 and cooperates with reduced parts or recesses 82 in the shank of the latch pin. The recesses 82 are spaced so that when the detent is engaged in one recess the pin is down as shown in Fig. 7, whereas when it is engaged in the other recess the pin is up and the latch free to release the plug.

In practice I preferably provide against leakage around the shaft 31. For instance, I may provide packing 83 around the shaft or in engagement with the head 70 of the shaft, as shown in Fig. 6, and I may provide suitable packing 84 around the other or projecting end of the shaft.

The indicating means 36 preferably provided in the construction may include a simple indicator 85 fixed on the projecting end of the shaft which indicator may be in the form of a pointer as shown in the drawings indicating the rotative position of the shaft so that the operator can readily determine whether the latch plate on the shaft is up as shown in Fig. 5 or down as shown in Fig. 8. In the preferred construction a guard flange 86 is provided on the housing to surround or protect the indicator 85, preventing accidental injury thereof.

The pressure equalizing means 16 that I have provided may be any suitable form of fluid piping

or the like, interconnecting the spaces in the head above, below and between the plugs. The piping that I have shown connects the chamber X above the plug A, the chamber Y between the plugs A and B, and connects with the interior of the head immediately below the plug B. The means 16 as shown in Fig. 3 of the drawings involves elbow fittings 100 communicating with the chamber X and communicating with the interior of the head immediately below the plug B, a T fitting 101 communicating with the chamber Y, and suitable pipe connections 102 between and joining the fittings.

The fluid supply means 17 that I have provided preferably includes a vertically disposed stand pipe 90 spaced to the one side of the body 10, a releasable coupling 91 on the lower end of the stand pipe for coupling it to a supply line such as a hose H, or the like, and a plurality of lateral branches 92, 93 and 94 coupling the stand pipe to the body 10 at different points vertically of the body, each of which branches is preferably under control of a valve or the like.

The coupling 91 like the coupling 11 provided on the body 10 may be any suitable quickly operable coupling and is provided primarily to serve as a means for making connections with a suitable supply line such as a pipe or hose. In the particular case illustrated the stand pipe is an assembly of parts or fitting selected to best suit the particular design illustrated. The number of lateral branches provided in the means 17 may vary with the number of plugs to be handled by the head and in a case where two plugs are to be handled, as shown in the drawings it is desirable to provide three such branches.

I have shown a branch 92 between the stand pipe and the chamber X provided between the upper end of plug A and the cap 12. I have shown a branch 93 between the stand pipe and the body 10 at a point to enter the body between the lower end of the upper plug A and the upper end of the lower plug B, it being important to observe that the latch engaged by both plugs serves to hold the plugs separated so that there is a space Y between them, with which the branch 93 communicates. The third branch 94 extends between the stand pipe and the body 10 at a point below the lower end of the lower plug B.

The stand pipe, like the several branches, is preferably a simple fluid conduit and these elements may be made up of suitable pipe fittings or connections. In the preferred form of the invention I provide a control valve for each branch of the means 17 and in the drawings I have shown a control valve 95 for the branch 92, a control valve 96 for the branch 93 and a control valve 97 for the branch 94. The valves 96 and 97 are directly connected in the branches 93 and 94 respectively, whereas in the preferred arrangement the valve 95 controlling branch 92 is located in the upper portion of the stand pipe above the branch 93, in which case a suitable connection or union 98 may be provided in the branch 92 as shown in Fig. 1 of the drawings. To facilitate assembly I provide a union 99 in the stand pipe between the branches 93 and 94. In practice the valves 95, 96 and 97 may be of any suitable form or type. In the drawings I have shown plug valves since this type of valve is simple, compact and easily operated.

In employing the construction that I have provided the head is handled by means of the line 75 so that it is maneuvered into a position over

the casing C and when in position the coupling 11 is operated to couple the body 10 to the casing C and the coupling 91 is operated to connect the stand pipe 90 with the supply line H. For sake of example it will be assumed that the head is employed to handle two plugs A and B and as the head is installed on the casing the plugs are in place as shown in Fig. 1, with the upper unit of means 15 holding the plugs A and B spaced apart to establish the chamber Y, this unit of means 15 serving to positively prevent downward movement of plug A and upward movement of plug B. The stop 13 positively prevents upward movement of plug A and the lower unit of means 15 positively prevents downward movement of the lower plug B.

As the head is put into operation fluid such as mud is circulated to the stand pipe 90 from the supply line H and the valve 97 is opened as indicated in Fig. 1 admitting such mud to the body 10 beneath the lower plug B so that the mud is circulated from the head down into the casing. The pressure equalizing means that I have provided equalizes the pressure between the several chambers. When it is desired to introduce other fluid such as cement into the well the valve 97 is closed, the valve 96 is opened, and the control pin of the means 15 supporting the lower plug B is released as indicated in Fig. 3. The desired fluid, say for instance cement, is introduced through the supply line H and the pressure thereof on the top of plug B forces the latch plate of the means 15 supporting the lower plug to the position shown in Fig. 8, so that the plug passes out of the head and into the casing.

When the desired amount of cement has been introduced the valve 96 is closed and the valve 95 is opened and the control pin of the uppermost unit of means 15 is released. Mud or other suitable fluid introduced through the line H is then conducted up through the stand pipe through the branch 92 and into the chamber X above the uppermost plug A so this plug is forced down through the body 10 past both of the units of the means 15 to enter the casing C and follow the body of cement down in the well, separating the cement and the mud introduced through the branch 93. By providing equalizing means I prevent damaging of the plugs while in the head due to differentials in pressure above and below the plugs which pressure might otherwise occur.

It will be apparent from the foregoing description that with my construction the plugs are effectively and dependably supported in the head ready for operation whenever the control pins are released, and it will be noted that the indicators of the means 15 are such that the operator can readily determine when the latch plates are moved to the released position by the plugs in order to make certain that the plugs have passed out of the head and into the casing.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A head of the character described including,

a vertically disposed tubular body adapted to carry a plug and having a side opening, and latch means carried by the body for preventing movement of the plug therein including a housing secured to the exterior of the body and forming a latch chamber in communication with the interior of the body through said opening, a shaft rotatably supported by the housing, a latch plate in the housing and fixed on the shaft to be projectable into the body, a spring normally yieldingly holding the latch plate in position projecting into the body and beneath the plug to support it in the body, and a releasable member carried by the housing engaging the shaft to positively hold it against rotation with the latch plate in said position.

2. A head of the character described including, a vertically disposed tubular body adapted to carry a plug and having a side opening, and latch means carried by the body for preventing movement of the plug therein including a housing secured to the body at the exterior thereof and forming a latch chamber in communication with the interior of the body through said opening, a shaft rotatably supported by the housing, a latch plate fixed on the shaft within the housing to be projectable into the body, a spring normally yieldingly holding the latch plate in projecting position where it extends into the body to engage beneath and stop the plug, indicating means on the shaft at the exterior of the housing revealing the position of the latch plate, and a releasable member carried by the housing normally engaging the shaft to positively hold it against rotation with the latch plate in said position.

3. A head of the character described including, a vertically disposed tubular body adapted to carry a plug and having a side opening, and latch means carried by the body for preventing movement of the plug therein including, a housing secured to the body at the exterior thereof and forming a latch chamber in communication with the interior of the body through said opening, a shaft rotatably supported by the housing, a latch plate fixed on the shaft in the housing, a spring normally yieldingly holding the latch plate in projecting position where it extends into the body where it engages beneath and stops the plug, and a pin slidably carried by the housing and manually shiftable into and out of position where it engages a flat side on the shaft to positively prevent rotation of the shaft from the position where the latch plate stops the plug.
